UNITED STATES PATENT OFFICE.

JOHN P. FRAZER, OF NEW YORK, N. Y.

IMPROVEMENT IN FASTENINGS FOR CHAMBER-DOORS.

Specification forming part of Letters Patent No. 36,563, dated September 30, 1862.

To all whom it may concern:

Be it known that I, JOHN P. FRAZER, of the city, county, and State of New York, have invented a new and useful Machine for the Securing of Doors from being Feloniously Entered from the Outside; and I do hereby declare that the following is a full, clear, and exact description of the construction and operation of the same, reference being had to the annexed drawings, in which—

Figure 1 is a perspective; Fig. 2, a view of the bolt-catch with the fastener in the place intended for the spring-bolt; and Fig. 3, the door closed, having the device attached.

I construct my fastener A, of brass, iron, or any other metal, about two inches long and three-fourths inch wide, with a support or hub on one end to act as a hook and on the other end a projection for a screw to pass through, with an opening down the center for the key. I then make a screw, B, the whole length to tighten the key in its place. I also make the key C about two inches long by three-eighths inch wide, with one straight edge, which is intended for doors with mortise-locks, (when the housing is finished with the wood-work,) and on the reverse I take a piece out of the center to make it fit the housing or lock-plate of box-locks, as in D. In inserting the fastener the screw must be drawn nearly its full length and the hook placed in the housing of either the spring or lock bolt. Then close the door, insert the key, and tighten with the screw, when the door will be effectually closed against any attempt from the outside, care being taken to adapt the key to the arrangement of the housing.

What I claim, and desire to secure by Letters Patent, is—

The adaptation of the hook-screw and key for the uses and purposes herein set forth.

JOHN P. FRAZER.
